UNITED STATES PATENT OFFICE.

SAMUEL MILLER MAVOR AND HENRY ALEXANDER MAVOR, OF GLASGOW, SCOTLAND, ASSIGNORS TO MAVOR AND COULSON, LIMITED, OF GLASGOW, SCOTLAND.

MINING-MACHINE.

1,100,597.

Specification of Letters Patent. Patented June 16, 1914.

Application filed March 8, 1910. Serial No. 548,099.

To all whom it may concern:

Be it known that we, SAMUEL MILLER MAVOR and HENRY ALEXANDER MAVOR, subjects of the King of Great Britain and Ireland, residing at 47 Broad street, Mile-End, Glasgow, in the county of Lanark, Scotland, have invented new and useful Improvements in Mining-Machines Particularly Adapted for Use in Mining Coal and the like, (for which we have made application for patent in Great Britain, No. 6,051, bearing date March 13, 1909, and No. 29,745, bearing date September 10, 1909,) of which the following is a specification.

15 In one system of mining minerals, hereinafter referred to as coal, it has been the practice to undercut the working face in the coal or in the underlying stratum, for which purpose various types of machines have been adopted. In one class of machine a laterally projecting cutter bar has been provided, to which a rotary, and in some cases also a reciprocatory motion, has been imparted.

25 In mining coal, the long wall method is usually adopted where possible. This method involves a long working face which is undercut by the cutting member as the machine is traversed from one end of the face to the other, and is usually only practicable under conditions where a shallow stratum is to be excavated. In view of the restricted height and space available behind the face in working a shallow stratum, the component parts of bar cutting machines have been arranged longitudinally, resulting in a comparatively long and narrow structure. In some cases these machines comprise a motor, electric or pneumatic for example, for operating the cutting bar, and haulage mechanism in addition thereto. In using machines of this type, the cutting bar, which may be located at, say, the trailing end of the machine, while being able to eat

45 into the working face approximately in line with the side wall at the entry end of the working, is unable to cut up to the side wall on the exit end of the working face, in consequence of the obstruction which the wall 50 on the exit side presents to the structure of the machine which protrudes in front of the cutting bar. In practice the machine is sometimes reversed in order to complete the cut. In consequence of the structural nature of machines of this type they are lie

convenient for use under conditions where a short face is to be worked; and the object of this invention is to produce an improved form of bar cutter machine, particularly adapted for use in short face workings, for example, as in heading operations or in working on the stall and pillar system, whereby the cutter bar is adapted to make an entry cut into the face in a line approximating to a continuation of the side wall, and to be traversed and withdrawn at the exit end of the face, completing the cut approximating to a continuation of the wall on the exit side.

According to this invention, a framework, which may comprise a casing, of comparatively short length and narrow width is provided and the component parts of mechanism for driving the rotary cutter bar, comprised in the construction of the machine, are placed in vertical arrangement, the cutter bar projecting laterally from the machine, and for use in conjunction with a machine of this form independent haulage apparatus may be provided, comprising a motor for driving haulage gear, and furnished with a traction connecting extending to the cutter machine, and provision may be made whereby the operations of the cutter machine and haulage mechanism are controlled from the cutter machine, and the haulage apparatus may be furnished with mechanism in order that it may be driven from one working to another, gearing being provided so that its motor may be arranged to impart suitable speeds to the haulage gear and bigger speeds if necessary, when the apparatus is required to act as a locomotive. In a modified form machines according to this invention of a type in which the rotary cutter bar has a reciprocatory motion imparted to it may be associated in construction with haulage apparatus comprising actuating gear operated by the reciprocatory action of the cutter bar.

In the accompanying drawings Figure 1 is a sectional elevation and Fig. 2 is a plan of a machine constructed in accordance with this invention and embodying the modification thereof. Fig. 3 is a plan illustrating the operation of a machine constructed according to this invention, and Fig. 4 is a plan illustrating the operation of a machine constructed in accordance with the modification thereof. Fig. 5 is a plan of a divided

bracing, Fig. 6 is a plan of gear for reciprocating a transverse shaft, and Fig. 7 is a part sectional plan of haulage drum reciprocating gear to be described.

5 According to this invention and as shown in the example of construction illustrated with reference to Figs. 1 and 2 a base casing A is provided to accommodate a transverse shaft B, (marked *each* to the left 10 tota) of the casing supported by a bearing gland C formed in the front wall of the casing, and by a central bearing C¹, which, as shown, may be cast in a part with the latter of the casing and be provided with 15 a bush. The cutter bar B¹, see Figs. 3 and 4, which constitutes an axial extension of the shaft B, is driven by means of a driven bevel wheel D, fitted on the shaft B, arranged in part with a driving bevel wheel D¹ located 20 above the central bearing about a vertical axis. The driving bevel wheel D¹ may, as shown in Figs. 1 and 5, be formed with a base bearing thrust collars embraced by a bearing D² having thrust recesses corresponding to the thrust collars on the base of the wheel D¹. The bearing D² is divided 25 into two parts, as shown in Fig. 5, to permit its application to the base of the wheel D¹, and the bearing D² is suspended by stand- 30 arms, which may depend from a diaphragm E, forming a cover to the base casing A. In the form illustrated, the diaphragm E is comprised in the construction of an intermediate casing A¹ surrounding the base A.

35 For imparting motion to the driving bevel wheel D¹, a vertical shaft G is provided, either in the form of construction illustrated 40 below, the head of the shaft being supported in a sleeve G¹ formed in the base of the bevel wheel D¹, or a feather end way as shown, the bearing being fitted between the shaft G and the driving wheel D¹. In order to support the shaft laterally, a spindle H is provided adapted to fit within the tubular shaft G, and having a flanged base which fits in a central aperture formed in a cover J applied to the head of a tubular casing A² which surrounds the intermediate casing A¹, a cylindrical axial extension being formed at 45 the foot of the spindle H adapted to rest in a correspondingly shaped formed in the upper part of the central bearing C¹. In addition where an electric drive is to be adopted, as in the example of construction illustrated 50 below, the rotor part viz., the armature K of the motor is carried upon the shaft G, a flange G² being formed thereon to provide a seat for the support of the armature, and the stator part viz., the field magnets K¹ of the rotor may be arranged concentrically around the armature, extending from the walls of the motor casing A². In a construction of this form, the parts may be so proportioned that the central spindle H, with 55 the cover J connected, may be removed so

that the shaft G with the armature K attached may then be drawn up through the open head of the casing A², the driving bevel wheel D¹ being left supported in the base of the casing. For lubricating the working parts, the spindle H may be centrally bored and formed with transverse conduits for the distribution of lubricant fed 70 at the front. The head of the spindle may be furnished with a removable cap H¹. In order to gain access to the driving and driven wheels, the base casing A is adapted to be disconnected from the intermediate casing A¹. In construction, the intermediate casing may be formed to provide accommodation for the reception of switches for controlling the cutter bar motor, and also, if desired, to accommodate switches for controlling the motor and gear operating mechanisms of the haulage apparatus. The base casing A may also serve as an oil receptacle for the gear wheels to work in, and for the accommodation of mechanism for imparting reciprocatory motion to the cutter bar shaft B which as shown at Fig. 6, may consist of a worm V, formed on the base of the driven bevel wheel D, arranged to mesh with two worm wheels V¹ V² each furnished with a crank pin V², from each of which a connecting rod V³ extends to one of two arms projecting from opposite sides of a collar V⁴ which embraces a sleeve V⁵ mounted upon a rearward prolongation B² of the shaft B. In action the rotation of the worm V rotates the worm wheels V¹ V² and causes the crank pins to transmit through the connecting rods V³, the collar V⁴ and the sleeve V⁵ reciprocatory motion to the shaft B. For the purpose of supporting a machine in cutting operation a sledge L may be provided, consisting, for example of a steel plate on which the machine is fixed, or the base of the machine may be formed to constitute a sledge. In the form of construction shown the sledge L has turned up 100 boundary edges to enable the machine to travel freely in any direction. In order that the cutting machine may be traversed from one position to another when not in cutting operation, supporting wheels, not shown in the drawings, may be provided arranged to be normally held out of action but, when required, adapted to be brought to bear upon the ground or upon rails provided for the wheels to run upon.

Machines constructed according to this invention as shown in the forms of construction illustrated may, as can best be seen at Figs. 3 and 4, have their cutter bars arranged to project from the front of the casing, radial adjustment being effected by sluing the frame. For directing the cutting machine guide bars M, see Figs. 3 and 4 may be provided, arranged, when the machine is required to make an entry cut, on 120

the sides thereof, one for example being set to bear against the side wall of the working the other on the opposite side against a fixed rail or props, and for effecting a cut along the working face the guide bars M may be set in front and behind, the rear bar bearing against a fixed rail or props set parallel to the working face. These guide bars may be connected to the machine by means, such, 19 for example, as links M', to permit them to be adjusted angularly and turned so as to assume positions at the sides or at the front and back of the machine as may be required.

As shown at Fig. 3 haulage apparatus N 15 is anchored and a flexible connection P, which may be a wire rope, carried around a pulley P' set at the exit end of the working face extending therefrom parallel to the working face, and passing around a pulley 20 P'' at the entry end of the working face, for use in cutting operation.

For traversing the machine from one place to another the machine may be pulled up to the haulage apparatus N, and the motor thereof thrown into gear for driving the supporting wheels of the haulage apparatus N.

Although the application of an electric motor has been described, it is to be understood that pneumatic or other forms of motors of concentric character may be used to drive the vertically arranged shaft G.

An example of the construction of a machine furnished with haulage mechanism 35 comprising actuating gear operated by connection with a rotary reciprocatory cutter member, will now be described with reference to Figs. 1, 2, 4 and 7 of the accompanying drawings. In the construction illustrated the rearward prolongation B² of the shaft B is arranged to project from the back of the base casing A, and haulage gear is provided consisting of a drum R located at the back of the machine, in association with 40 actuating gear comprising connecting rods S extending from arms projecting from the sides of a collar W mounted upon the sleeve V² near the end of the prolongation B² fitted with pins S' arranged to operate two oscillating ratchet members T T', mounted coaxial to the haulage drum R, which are furnished with ratchet mechanisms arranged to operate upon a peripheral ratchet race R' formed on the drum. In action the 45 ratchet mechanism of the member T acts when turned forward and the member T' acts when turned backward.

What we do claim as our invention, and desire to secure by Letters Patent, is:—

60 1. In a mining machine, the combination with a framework and a rotary cutter-bar shaft provided with a driven-gear wheel, of means for operating the cutter bar, said means comprising a vertical driving shaft, 65 a rotor fixed to said driving-shaft, a driv-

ing-gear wheel, means for holding the driving-gear wheel in mesh with the driven-gear wheel, said driving-gear wheel having a tubular boss engaged by said holding means and receiving the lower end of the vertical shaft, and interengaging connections between the vertical shaft and the boss of the driving-gear wheel, said connections holding the parts rotatably together and permitting the endwise removal of the vertical shaft relatively to and without disturbing the position of the driving-gear wheel.

2. In a mining machine, the combination with a framework, and a rotary cutter-bar shaft provided with a gear-wheel, of means for operating the cutter-bar shaft, said means comprising a gear-wheel meshing with the first-named gear-wheel and provided with a tubular boss, and having its axis at right-angles to the cutter-bar shaft, 80 means connected to the framework and engaging said boss for holding the second-named gear-wheel in position in mesh with the first-named gear-wheel, a vertical shaft and a rotor fixed thereto, and a vertical key-and-way connection between the lower part of the vertical shaft and the inner wall of said boss for detachably locking the shaft to the boss and permitting the shaft with its rotor to be removed from the framework 85 relatively to and without disturbing the position of the driving gear-wheel.

3. In a mining machine, the combination with a framework and a rotary cutter-bar shaft provided with a gear-wheel, of means for operating the cutter-bar shaft, said means comprising a gear-wheel in mesh with the first-named wheel and having a tubular boss, a vertical shaft provided with a rotor and having its lower end entering said boss, a key-and-way connection between the lower end of the vertical shaft and the boss permitting the vertical shaft and its rotor to be removed relatively to the second gear-wheel, and means independent of said shaft 100 for holding the second-named gear wheel in position and in mesh with the first-named gear-wheel, when the vertical shaft is removed.

4. In a mining machine, the combination with a framework and a rotary cutter-bar shaft provided with a gear-wheel, said framework having an opening of large dimensions in its upper end, and a cover-plate forming a closure for said opening, of means for operating the cutter-bar shaft, said means comprising a gear-wheel having its axis at right-angles to the first-named gear-wheel, and provided with a tubular boss, means fixed to the framework and engaging said boss for holding the second-named gear-wheel in position and in mesh with the first-named gear-wheel, a vertical shaft and a rotor thereon, said shaft having its lower end adapted to enter the boss of the 115 120 125 130 135 140 145 150 155 160 165 170 175 180

- second-named gear-wheel, and a slidable connection between the shaft and the boss for locking the parts rotatably together while permitting the endwise removal of the 5 shaft relatively to and without disturbing the position of the second-named gear-wheel.
5. In a mining machine, the combination with a framework and a rotary cutter-bar shaft provided with a gear-wheel, said 10 framework having an opening of large dimensions in its upper end, and a cover-plate forming a closure for said opening, of means for operating the cutter-bar shaft, said means comprising a gear-wheel having 15 its axis at right angles to the first-named gear-wheel, and provided with a tubular boss, means fixed to the framework and engaging said boss for holding the second-named gear-wheel in position and in mesh 20 with the first-named gear-wheel, a vertical shaft and a rotor thereon; said shaft having its lower end adapted to enter the boss of the second-named gear-wheel, and a slidable connection between the shaft and the boss 25 for locking the parts rotatably together while permitting the endwise removal of the shaft relatively to and without disturbing the position of the second-named gear-wheel, said cover plate having an extended 30 spindle adapted to enter the tubular shaft and support the same laterally.
6. A mining machine, comprising a framework, a rotary cutter-bar shaft extending laterally across the framework, means for reciprocating the cutter-bar shaft, a driving shaft disposed at right-angles to the cutter-bar shaft, means for transmitting radial motion from the driving-shaft direct to the cutter-bar shaft, a haulage drum, and connections between the said drum and the 35 cutter-bar shaft for converting the reciprocations of said shaft into rotary movement of the drum.
7. A mining machine, comprising a framework, a rotary cutter-bar shaft extending laterally across the framework, means for reciprocating the cutter-bar shaft, a driving-shaft disposed at right-angles to the cutter-bar shaft, means for transmitting rotary motion from the driving-shaft direct to the cutter-bar shaft, a haulage drum provided with a ratchet-wheel, pawls engaging said ratchet-wheel, and connections between the pawls and the cutter-bar shaft whereby the reciprocations of the latter shaft are transmitted through the pawls and ratchet to rotate the haulage drum. 45
8. A mining machine comprising a framework, a rotary cutter-bar shaft extending laterally across the framework, an elongation from the rear end of the cutter-bar shaft, means for reciprocating the cutter-bar shaft, a driving-shaft disposed at right-angles to the cutter-bar shaft, means for transmitting rotary motion from the driving-shaft direct to the cutter-bar shaft, the driving-shaft constituting the drive-shaft of a power motor, a haulage drum and gear for actuating the drum extending from the end of the prolongation of the cutter-bar 50 shaft, for the purposes set forth.
